(74) Attorney, Agent, or Firm — Sand, Sebolt & Wernow
Co., LPA(57) **CLAIM**

The ornamental design for a pen, as shown and described.

DESCRIPTION

FIG. 1 is a top, front right isometric perspective view of a first embodiment of a pen in accordance with my design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.

The broken lines illustrate portions of the pen which form no part of the claimed design.
